(57) **CLAIM**

I claim the ornamental design for a pouring funnel for a bottle, as shown and described.

DESCRIPTION

FIG. 1 shows a perspective view of my invention for a pouring funnel for a bottle.

FIG. 2 is a front elevation view.

FIG. 3 is a side elevation view looking from the left side of FIG. 1.

FIG. 4 is a top plan view.

FIG. 5 is a side elevation view looking from the right side of FIG. 1 opposite from that shown in FIG. 3.

FIG. 6 is a rear elevation view opposite that shown in FIG. 2; and,

FIG. 7 is a bottom plan view looking upwardly.
